ANCHOR FOR HOLDING UNDER TENSION THE
EMBEDDED CABLES OF A PRESTRESSED CON-
CRETE GIRDER

George J. Eriksson, Morton Grove, Ill., assignor to Su-
perior Concrete Accessories, Inc., Franklin Park, Ill., a
corporation of Delaware

Filed May 31, 1963, Ser. No. 75,126

Term of patent 14 years

(Cl. D54—9)

FIG. 1

FIG. 2

FIG. 3

FIG. 4

FIG. 5

FIG. 1 is a top perspective view of an anchor for hold-
ing under tension the embedded cables of a prestressed
concrete girder, said device embodying my new design;

FIG. 2 is a front view;

FIG. 3 is a side view;

FIG. 4 is a top plan view; and

FIG. 5 is a bottom plan view thereof.

I claim:

The ornamental design for an anchor for holding under
tension the embedded cables of a prestressed concrete
girder, substantially as shown.
